Primary Examiner — Caron D Veynar*Assistant Examiner* — Abraham Bahta(74) *Attorney, Agent, or Firm* — Cook Alex Ltd.(57) **CLAIM**

The ornamental design for a catheter package, as shown and described.

DESCRIPTION

FIG. 1 is a perspective view of a catheter package, showing the new design;

FIG. 2 is a front plan view of the catheter package of FIG. 1; FIG. 3 is a rear plan view of the catheter package of FIG. 1; FIG. 4 is a left side elevational view of the catheter package of FIG. 1;

FIG. 5 is a right side elevational view of the catheter package of FIG. 1;

FIG. 6 is a top plan view of the catheter package of FIG. 1; and,

FIG. 7 is a bottom plan view of the catheter package of FIG. 1.
